UNITED STATES PATENT OFFICE.

CLAUDE HÉME, OF BAY CITY, MICHIGAN.

SALT-GRAINER.

SPECIFICATION forming part of Letters Patent No. 278,794, dated June 5, 1883.

Application filed October 16, 1882. (No model.)

To all whom it may concern:

Be it known that I, CLAUDE HÉME, of Bay City, in the county of Bay and State of Michigan, have invented new and useful Improvements in Salt-Grainers; and I do hereby declare that the following is a full, clear, and exact description thereof, reference being had to the accompanying drawing, which forms a part of this specification.

10 The nature of this invention relates to certain new and useful improvements in devices for the manufacture of salt by steam-evaporation in what are ordinarily termed "salt-grainers," by means of which the salt, as fast as precipitated, is automatically removed from the grainer, and the brine is agitated by the devices employed for so removing the salt, such agitation greatly facilitating the process of precipitation.

20 The invention consists in the peculiar construction, combination, and operation of parts, as more fully hereinafter set forth.

In the accompanying drawing, which forms a part of this specification, my invention is 25 shown as applied to a grainer.

A represents a grainer of the ordinary construction, except as hereinafter described, the floor of which, at the discharge end, terminates in an upwardly-inclined plane. Upon 30 each inner side wall of the grainer there is secured, in the usual way and above the level of the brine, a rail, B, upon the top of which travel the carrying-bars C, which are each made in two parts, which are jointed together,

35 as shown at a. Secured to each of these bars, and coincident upon the opposite sides, are the hanging supports D, the lower ends of which nearly approach the floor of the grainer. To the front of each pair of these bars is pivotally 40 secured the hoes e, the length of which corresponds to the width of the floor of the grainer. These hoes are so attached to the pendent arms that in the forward reciprocation toward the inclined end of the grainer the hoes will be in 45 a vertical position, resting against the front faces of their supports, and with their lower edges upon, or nearly so, the bottom of the grainer. In the reverse motion of the travel resistance of the brine will cause these hoes to 50 assume a horizontal position until its portion of the travel is completed.

The object of jointing the carrying-bars C,

as described, is to enable the front hoe to travel up the inclined plane x and force the salt over the front end of the grainer in the travel of the 55 hoes.

F are a pair of sprocket-wheels, one being secured near each end of the shaft G, the ends of the shaft being suitably journaled in boxes upon the opposite sides of the grainer, and to 60 one of the projecting ends of this shaft, by means of a crank or pulley, motion is imparted.

H are two grooved pulleys, although these latter may be sprocket-wheels, if preferred, 65 secured upon the shaft I, journaled as described with reference to the shaft G.

J are sprocket-chains running over the sprocket-wheels and pulleys—one upon each side of the grainer—and each one of these chains 70 has projecting on either side and coincident in both chains a small stud, b, upon each of which is placed a small roller. In the rotation of these sprocket-wheels and chains these friction-wheels upon the studs b come in contact with 75 the forks c upon the ends of the rods d, the opposite ends of which are secured to the risers K, the lower ends of which are rigidly secured to the carrying-bars, so that in the rotation of the chains the hoes will be withdrawn to the 80 rear end of the grainer. In the further rotation of the chains these small studs b, with their wheels, will engage with projections o on the carrying-bars and force the hoes toward the front end of the grainer, carrying the deposited 85 salt with them.

In order to prevent any uncertainty in this description, the front end of the grainer is that one wherein the floor terminates in the upwardly-inclined plane. The upper edges of 90 these hoes terminate in teeth f, which project to the surface of the brine, and the intervals between the teeth in each of the hoes being coincident, they pass in their travel between the steam-pipes—such as are usually found in 95 grainers—so that when the hoes are in the act of withdrawing the salt their projecting teeth act as agitators of the surface of the brine. The front hoe and its connections differ from the others in the series. This hoe is pivoted to a 100 bar, D', which is provided with a friction-roller, m, and is secured to the short arm of the carrying-frame C in front of the pivot a. The roller m rides up a track, M, of the same

incline as the front end of the grainer, and thus allows this front hoe to take the salt from the succeeding hoes and force it over the end of the grainer.

5 I am aware of Patent No. 267,085, issued to Andrew Johnson, November 7, 1882, and make no claim to the construction shown therein.

What I claim as my invention is—

10 1. The pivoted hoes *e*, having agitating fingers *f*, combined with means, substantially as described, for imparting to said hoes a reciprocating motion, whereby the salt is forced in one direction automatically, and the fingers *f* automatically agitate the brine to assist granulation, as specified.

2. The front hoe, *e*, and support *D'*, having roller *m*, combined with the jointed carrying frame *C a*, rail *M*, and incline *x*, as and for the purpose set forth.

3. The sprocket-wheels *F H* and endless chains *J*, having studs *b*, provided with friction-wheels, combined with the carrying-frame *C*, risers *K*, and rod *d*, having forked end *c*, as and for the purposes specified.

CLAUDE HÉME.
